GAME BOARD

Fred W. Leonow, Cleveland, Ohio

Application February 16, 1948, Serial No. 144,519

Term of patent 14 years

(Cl. D34—5)

To all whom it may concern:

Be it known that I, Fred W. Leonow, a citizen of the United States and a resident of Cleveland, in the county of Cuyahoga and State of Ohio, have invented a new, original, and ornamental Design for a Game Board, of which the following is a specification, reference being had to the accompanying drawing, forming part thereof.

The figure is a plan view of a game board showing my new design. The game board is of conventional thickness and the ornamentation thereon represents surface markings only.

I claim:

The ornamental design for a game board, as shown and described.

FRED W. LEONOW.
